United States Patent Office

Des. 228,900

Patented Oct. 30, 1973

228,900

IN-WALL FIRE EXTINGUISHER

John M. Hogg, 537 Madison St., Albany, Calif. 94706

Filed June 7, 1971, Ser. No. 150,894

Term of patent 14 years

Int. Cl. D29—01

U.S. Cl. D16—2 A

FIG. 2

FIG. 4

FIG. 1

FIG. 3

FIG. 5

FIG. 1 is a front view of an in-wall fire extinguisher with portions fragmentarily cut away and shown in cross-section for clarity of illustration;

FIG. 2 is a top plan view thereof;

FIG. 3 is a right side elevational view thereof;

FIG. 4 is a left elevation thereof with fragmentary portions cut away and shown in cross-section; and

FIG. 5 is a bottom plan view thereof.

I claim:

The ornamental design for an in-wall fire extinguisher, as shown and described.
